ELECTROMAGNETIC GAS REGULATING AND
IGNITING ATTACHMENT

John G. Neumann, Abilene, Tex.

Application March 15, 1932, Serial No. 599,053

11 Claims. (Cl. 137—139)

This invention relates to an electro-magnetic gas regulating and igniting attachment designed primarily for use in connection with gas stoves, but it is to be understood that an attachment, in accordance with this invention may be employed for any purpose for which it is found applicable, and the invention has for its object to provide, in a manner as hereinafter set forth, an attachment for igniting a gas burner and regulating a gas supply by remote control.

To the above ends essentially and to others which may hereinafter appear, the invention consists of such parts and combination of such parts as fall within the scope of the invention as claimed.

In the drawings:

Figure 1 is a vertical sectional view of an electromagnetic gas regulating and igniting attachment in accordance with this invention with the controlling and regulating valve thereof shifted from its normally closed position to open position, and further illustrating, by way of example, the arrangement of the igniting element with respect to a gas burner, the latter being shown in dotted lines.

Figure 2 is a section on line 2—2 Figure 1.

Figure 3 is a section on line 3—3 Figure 1.

Figure 4 is a section on line 4—4 Figure 1.

Figure 5 illustrates in elevation a detail of the control element.

Figure 6 is a sectional detail of the regulating element.

The attachment includes a gas regulating element 1, an igniting element 2 and a control element 3. The elements 1 and 2 are in circuit with the element 3.

The circuit conductors of a service line are indicated at 4, 5 and which lead from an electrical source, not shown. As shown by way of example, the conductors 4, 5 are attached to a plug 6 for seating in a wall socket. The conductor 4 leads to element 3. The conductor 5 is branched, as at 5', one branch 77 leading to element 1 and the other to element 2. The branch leading to element 1 is also branched as at 7, 7'.

The element 1 comprises a suitably insulated casing 8 which is interposed in and connected to a gas supply line. The sections of the line with which casing 8 is arranged between are indicated at 9, 10, the former leads from a source of gas supply, not shown and the latter to the burner 11. Casing 8 has secured to its outer periphery on opposite sides thereof, coupling members 12, 13 for the line sections 9, 10 respectively. The member 12 is arranged above member 13. With-

in casing 8 is arranged a diametrically extending gas intake pipe 14 which leads from line section 9. Positioned within the upper portion of casing 8, is a regulating valve mechanism 15, comprising a housing 16 opening at its top and bottom and provided between its transverse median and its upper end with a partition 17, to form that part of the housing above the partition as a gas intake chamber 18 into which opens the pipe 14 at a point in proximity to partition 17, the latter being formed axially thereof with an opening 19 providing a valve stem guide. The housing 16 at a point between its transverse median and lower end is formed with a partition 20 provided with an axially arranged opening 21 having its wall beveled to form a valve seat 22. That part of the housing below partition 20 provides a gas discharge chamber 23. The intermediate portion of the housing is of greater diameter than its upper and lower portions and in connection with the partitions 17 and 20 provides a valve chamber 24. The chamber 18 is closed by a removable plug 25. Casing 8 has an opening 26 in its top so that access can be had to plug 25. Arranged within chamber 24 for engaging valve seat 22 to shut off communication between chambers 23 and 24 is a controlling valve 27 formed integral with the lower end of a stem 28, which extends upwardly through opening 19. The valve 27 is normally in closed position to shut off the gas supply to the burner and is illustrated as being shifted to open position. When in its normal position it engages the valve seat 22. The valve 27 is also formed with a lower depending pronged tubular stem 29 which passes through opening 21. Disposed diametrically of housing 3 and opening into chamber 23 is a gas discharge pipe 30 which communicates with line section 10.

Positioned in casing 8 is a pair of solenoids 31, 32 having their cores designated 33, 34 respectively. The cores constitute plungers. The branches 7, 7' of circuit conductor 5 are connected to solenoids 31, 32 respectively. Within casing 8 is arranged a receptacle of non-magnetic material formed of a head part 35 and a pair of depending spaced tubular extensions 36, 37 which extend through and frictionally engage with the solenoids 31, 32 respectively and have operating therein the cores 33, 34 respectively. The extensions open into the head part 35 and the latter has an opening 38 in its top and a vertical collar 39 registering with the wall of opening 38. The collar 39 extends into the bottom of and is secured to housing 16. The lower ends of the tubular extensions are plugged as at 40.

insulated and snugly fitted on the tubular extensions. The solenoids are adjusted upon the extensions a small distance above the point where they have the greatest pulling power and such adjustment can be had with little pressure. The cores are at their highest points when adjustment of the respective solenoid coils are made. This adjustment makes it possible to raise or lower the valve 27 gradually. Now it will be assumed that the current is flowing in each solenoid, but more into solenoid 32 which holds valve 27 open, and it is desired to close the latter. The current in solenoid 32 is gradually diminished, while that in solenoid 31 gradually increases, whereby instead of core 33 being sucked or pulled in with a jerk it will move in where the magnetic influence is less for a given current and core 34 moves out where the magnetic influence is greater for a given current and equilibrium is again established. Extending to the solenoids 31, 32 from element 3 are also circuit conductors 48, 49 respectively.

The element 2 includes a metallic casing 50 in which is arranged a vibratory induction coil 51 of the condenser type and which is insulated from casing 50, as at 52, 53 and 54. Insulating means 54 is formed with a pair of openings 55, 56. Arranged within casing 50 and below the means 54 is a transformer 57 of the small bell ringing type. When an alternating current of 110 to 120 volts is passed into the transformer a low voltage current is taken off the secondary winding by the leads 58, 59 which are connected to terminals 60, 61 respectively of the induction coil 51. One of the leads 58 or 59 is connected to the casing 50 and in this particular case terminal 61 is connected to the casing 50. The high tension terminal 62 is then connected to a spark plug 63 which would be located just above the mouth of the burner 11. The return circuit is made through the stove casing 50 and the terminal 61.

The element 3 consists of an ordinary high resistance rheostat 64 arranged in a casing 65 and including a spring controlled, rotatable and longitudinally shiftable shaft 66 provided at its outer end and adjacent casing 65 with a fixed knob 67. Within casing 65 is arranged a manually operated, pivoted, spring controlled circuit opening and closing member 68 and a contact 69. The members 68 and 69 constitute a safety switch. Within casing 65 is a binding post 70 which carries a resilient conductor member 71 encompassing and bearing against shaft 66. Leading from contact 69 to post 70 is a circuit connection 72. The

mechanism is arranged a filler 83 of sealing or insulating material. The pipes 14 and 30 extend through the means 90 and 82 respectively and also the filler 83. The filler 83 also extends down into the lower portion of casing 8 filling the space between the regulating valve mechanism and casing 8. The filler 83 is added after the final adjustment of the solenoids has been made. The filler 83 holds the solenoids rigid and makes them non-adjustable.

The elements 1 and 2 are placed within the stove if the latter permits, if not they are bolted on the outside of the stove. The controlling element 3 is positioned at a point remote from elements 1 and 2.

When the stove is to be ignited, the contact arm 73 is turned opposite terminal 74 and pushed in, that is to say after member 68 is moved to engage contact 69 and whereby current is passed to the transformer 57 and solenoid 32 which causes the valve to open allowing gas to be supplied to the burner and is ignited by the spark plug. The valve 27 will remain in open position for supply of gas until it is desired to cut off the supply to the burner. After the valve 27 has been adjusted to its open position to the desired extent, the current is shut off from the solenoids by opening switch 68 and the valve will be held in such position. In order to close valve 27, the operator will close switch 68, press in knob 67 causing arm 73 to make contact with the resistance wire of the rheostat. The operator will then turn knob 67, when arm 73 is in contact, in a clockwise direction. This operation diminishes the resistance in the circuit to which solenoid 31 is a part and at the same time increases the resistance in the circuit in which solenoid 32 is a part. This causes more current to flow in solenoid 31 thus producing a greater magnetic field about solenoid 31 than that produced about solenoid 32, this causing core 33 to be drawn in solenoid 31 which provides for solenoid 31 acting to close valve 37. The operator releases knob 67 permitting it to swing outwardly to cut off the current. Knob 67 is then turned by the operator counter-clockwise to its initial position whereby when again turned in a clockwise direction to the desired extent while pressed in, it will provide for the opening of valve 37 when desired. Core 34 is of slightly greater length than core 33 and which in addition to the weight of valve 27 will balance lever 42 resulting in the non-opening of valve 27 when the current is cut off. The valve 27 is shifted from closed to open position and

from open to closed positions respectively by the action of the solenoids 32, 31.

The lever 42 remains in whatever position it is shifted previous to the cutting off the current, and it is also held in place by the slight tension of its supports 41 bearing thereagainst. The current is cut off when the valve 37 is adjusted for supply and also after the valve has been shifted to closed position.

10. What I claim is:—

1. In an electro-magnetic gas regulating attachment, a regulating valve structure adapted to be interposed in a gas conducting line for controlling the passage of gas through the latter and including a valve capable of being shifted from closed position to open position and from open position to closed position and temporarily maintained in any one of the positions to which it has been shifted, a non-magnetic receptacle below said valve, opening at its top into the outlet side of said structure and including a pair of depending tubular extensions closed at their outer ends, solenoids encompassing and having their cores slidably mounted in said extensions, a layer pivotally mounted in said receptacle and connected in proximity to its pivot with said valve for shifting the latter, said cores being attached to the ends of and formed to balance said lever, and current controlling means having provisions common to said solenoids to cause the actuation of the lever in a direction to gradually shift said valve from closed to open position and subsequently to the shifting of the valve from closed to open position to cause the magnetic force of one of the solenoids overcoming the magnetic force of the other solenoid to provide for the actuation of the lever in a direction to shift the valve from open to closed position, one of the solenoids having its core of greater length than the other.

45. 2. In an electro-magnetic gas regulating attachment, a regulating valve structure adapted

to be interposed in a gas conducting line for controlling the passage of gas through the latter and including a valve capable of being shifted from closed position to open position and from open position to closed position and temporarily maintained in any one of the positions to which it has been shifted, a non-magnetic receptacle below said valve, opening at its top into the outlet

side of said structure and including a pair of depending tubular extensions closed at their outer ends, solenoids encompassing and having their cores slidably mounted in said extensions, a lever pivotally mounted in said receptacle and connected in proximity to its pivot with said valve for shifting the latter, said cores being attached to the ends of and formed to balance said lever,

current controlling means having provisions common to said solenoids to cause the actuation of the lever in a direction to gradually shift said valve from closed to open position and subsequently to the shifting of the valve from closed to open position to cause the magnetic force of one of the solenoids overcoming the magnetic force of the other solenoid to provide for the actuation of the lever in a direction to shift the valve from open to closed position, a casing common to said structure, solenoids and receptacle

80 and insulated therefrom, and said structure opening through opposed walls of said casing.

60. 3. In an electro-magnetic gas regulating attachment, a regulating valve structure adapted to be interposed in a gas conducting line for controlling the passage of gas through the latter and including a valve capable of being shifted from closed position to open position and from open position to closed position and temporarily maintained in any one of the positions to which it has

and for maintaining the valve in closed position when the solenoids are de-energized by said current controlling means, and said solenoids being adjusted on said extensions a small distance above the point where they have the greatest pulling power on their cores.

85. 3. In an electro-magnetic gas regulating attachment, a regulating valve structure adapted to be interposed in a gas conducting line for controlling the passage of gas through the latter and including a valve capable of being shifted from closed position to open position and from open position to closed position and temporarily maintained in any one of the positions to which it has been shifted, a non-magnetic receptacle below said valve, opening at its top into the outlet side of said structure and including a pair of depending tubular extensions closed at their outer ends, solenoids encompassing and having their cores slidably mounted in said extensions, a lever pivotally mounted in said receptacle and connected in proximity to its pivot with said valve for shifting the latter, said cores being attached to the ends of and formed to balance said lever, and current controlling means having provisions common to said solenoids to cause the actuation of the lever in a direction to gradually shift said valve from closed to open position and subsequently to the shifting of the valve from closed to open position to cause the magnetic force of one of the solenoids overcoming the magnetic force of the other solenoid to provide for the actuation of the lever in a direction to shift the valve from open to closed position, one of the solenoids having its core of greater length than the other.

100. 4. In an electro-magnetic gas regulating attachment, a regulating valve structure adapted to be interposed in a gas conducting line for controlling the passage of gas through the latter and including a valve capable of being shifted from closed position to open position and from open position to closed position and temporarily maintained in any one of the positions to which it has been shifted, a non-magnetic receptacle below said valve, opening at its top into the outlet

side of said structure and including a pair of depending tubular extensions closed at their outer ends, solenoids encompassing and having their cores slidably mounted in said extensions, a lever pivotally mounted in said receptacle and connected in proximity to its pivot with said valve for shifting the latter, said cores being attached to the ends of and formed to balance said lever,

current controlling means having provisions common to said solenoids to cause the actuation of the lever in a direction to gradually shift said valve from closed to open position and subsequently to the shifting of the valve from closed to open position to cause the magnetic force of one of the solenoids overcoming the magnetic force of the other solenoid to provide for the actuation of the lever in a direction to shift the valve from open to closed position, a casing common to said structure, solenoids and receptacle

115 and insulated therefrom, and said structure opening through opposed walls of said casing.

120. 5. In an electro-magnetic gas regulating attachment, a regulating valve structure adapted to be interposed in a gas conducting line for controlling the passage of gas through the latter and including a valve capable of being shifted from closed position to open position and from open position to closed position and temporarily maintained in any one of the positions to which it has

125 and for maintaining the valve in closed position when the solenoids are de-energized by said current controlling means, and said solenoids being adjusted on said extensions a small distance above the point where they have the greatest pulling power on their cores.

130. 5. In an electro-magnetic gas regulating attachment, a regulating valve structure adapted to be interposed in a gas conducting line for controlling the passage of gas through the latter and including a valve capable of being shifted from closed position to open position and from open position to closed position and temporarily maintained in any one of the positions to which it has

135 and for maintaining the valve in closed position when the solenoids are de-energized by said current controlling means, and said solenoids being adjusted on said extensions a small distance above the point where they have the greatest pulling power on their cores.

140. 5. In an electro-magnetic gas regulating attachment, a regulating valve structure adapted to be interposed in a gas conducting line for controlling the passage of gas through the latter and including a valve capable of being shifted from closed position to open position and from open position to closed position and temporarily maintained in any one of the positions to which it has

145 and for maintaining the valve in closed position when the solenoids are de-energized by said current controlling means, and said solenoids being adjusted on said extensions a small distance above the point where they have the greatest pulling power on their cores.

150. 5. In an electro-magnetic gas regulating attachment, a regulating valve structure adapted to be interposed in a gas conducting line for controlling the passage of gas through the latter and including a valve capable of being shifted from closed position to open position and from open position to closed position and temporarily maintained in any one of the positions to which it has

- 20 to cause the magnetic force of one of the solenoids overcoming the magnetic force of the other solenoid to provide for the actuation of the lever in a direction to shift the valve from open to closed position, said cores and lever having coacting means for maintaining the valve in open position when the solenoids are de-energized by said current controlling means and for maintaining the valve in closed position when the solenoids are deenergized by said current controlling means, a casing common to said structure, solenoids and receptacle and insulated therefrom, and said structure opening through opposed walls of said casing. 95
- 25 8. In an electro-magnetic gas regulating attachment, a regulating valve structure for interposition in a gas conducting line for controlling the passage of gas through the latter and including a valve capable of being shifted from closed position to open position and from open position to closed position and temporarily maintained in any one of the positions to which it has been shifted, a non-magnetic receptacle below the valve, opening at its top into the outlet side of 100 said structure and including a pair of depending tubular extensions, a lever pivotally mounted intermediate its ends within said receptacle, connected to said valve and having its ends disposed over said extensions, solenoids surrounding and having the cores thereof slidably within said extensions, said cores being attached to the ends of and being formed to balance said lever, and a controlling device for the pair of solenoids including means substantially as described having 105 provisions for respectively energizing the solenoids to provide for the shifting of the lever in a direction to gradually move the valve from a closed position to an open position; for de-energizing the solenoids to cause the valve to remain 110 in such open position; for energizing the solenoids to provide for the shifting of the lever in a direction to gradually move the valve from such open position to closed position; and for de-energizing the solenoids to maintain the valve in 115 closed position. 120
- 30 9. In an electro-magnetic gas regulating attachment, a regulating valve structure for interposition in a gas conducting line for controlling the passage of gas through the latter and including a valve capable of being shifted from closed position to open position and from open position to closed position and subsequently to the shifting of the valve from closed to open position to cause the magnetic force of one of the solenoids overcoming the magnetic force of the other solenoid to provide for the actuation of the lever in a direction to shift the valve from open to closed position, said cores and lever having coacting means for maintaining the valve in open position when the solenoids are de-energized by said current controlling means and for maintaining the valve in closed position when the solenoids are deenergized by said current controlling means, said solenoids being adjusted on said extensions a small distance above the point where they have 125 the greatest pulling power on their cores, a casing common to said structure, solenoids and receptacle and insulated therefrom, and said structure opening through opposed walls of said casing. 130
- 35 7. In an electro-magnetic gas regulating attachment, a regulating valve structure adapted to be interposed in a gas conducting line for controlling the passage of gas through the latter and including a valve capable of being shifted from closed position to open position and from open position to closed position and temporarily main- 135
